UNITED STATES PATENT OFFICE.

LEWIS WM. HASSELMAN, OF INDIANAPOLIS, INDIANA.

STRAW-STACKER.

SPECIFICATION forming part of Letters Patent No. 290,050, dated December 11, 1883.

Application filed April 16, 1883. (No model.)

To all whom it may concern:

Be it known that I, LEWIS W. HASSELMAN, of Indianapolis, Indiana, have invented a new and useful Improvement in Straw-Stacking Machines, of which the following is a description, reference being made to the accompanying drawings, in the several figures of which like letters indicate like parts.

My invention relates to that class of machines known as "stackers," and is designed to be used in connection with straw-thrashing machines.

In the drawings, Figure 1 is a side elevation of my machine mounted on trucks; Fig. 2, a top view with the folding carrier and its gearing removed, and Fig. 3 a rear end view. Fig. 4 is a side elevation of the rear end of the elevator, and Fig. 5 is a cross-section of the same.

20 The machine as herein described is an improvement on my first straw-stacker, for which Letters Patent No. 274,940 were issued to me on the 3d day of April, 1883.

In detail, *c* is a folding carrier, which has a 25 slatted belt, *b*, moved by a belt upon the two pulleys *dp* and *dp'*, which are actuated by the bevel-gears *b'* and *b''*, the former mounted on the horizontal shaft *s*, and the latter on a vertical shaft.

30 *a*, *a'*, *a''*, and *a'''* indicate the parts of the framework of the carrier. The carrier and its frame revolve upon the fifth-wheel *fw*, and are supported on the top of a rigid frame-work, *F* *F'*, through the top plate of which passes a vertical shaft, on the upper end of which is fixed the bevel-gear *b'*, and on its lower end the bevel-gear *b''*. This vertical shaft passes through a sleeve or hub, *hu*, as shown in Fig. 3. The bevel-gear wheel *b''* engages with the 40 bevel-wheel *b'''*, Fig. 3, which latter is mounted on the end of the short shaft *s'*, having a bearing in the hanger *ha*, and on the outer end of this shaft *s'* is fixed the main driving-pulley *dp'*, from which a belt, *bt'*, leads to the pulley on the engine.

45 *ch* is a chain attached to a projection, *P*, on the end of the carrier, and winding on a spool or windlass, *sp*, with cogged gearing *cg* and *cg'*, for revolving it by means of the crank *cr*. This apparatus is for raising and lowering the carrier.

W is a counter-balance.

*s*⁵ is a ratchet on the outer end of shaft *s*³. *s*⁴ is a pawl on the outside of the frame *F*, which engages the ratchet *s*⁵. By turning the crank *cr* the cogs *cg* *cg'* are revolved, and the chain *ch* wound upon the windlass *sp*, and the elevator thereby raised. The pawl and ratchet prevent the backward movement of the windlass. The receiving end of the carrier-frame is hopper-shaped; but its sides, instead of being rigid, are foldable inwardly, as shown in Figs. 4 and 5. In the drawings, *st* is a strap bolted to the upper section of the hopper's side, and *hi* is a hinge, by which the two parts are connected.

When the machine is to be transported, the hinged sides are folded inward, as indicated by dotted lines in Fig. 5.

What I claim, and desire to secure by Letters Patent, is—

1. In a straw-stacking machine, a carrier-frame consisting of a flat bottom, rigid upwardly-projecting sides, flaring hinged top boards, and straps secured to the outside of said boards, the lower ends of said straps extending below the bottom of said boards, whereby the top hinged boards are adapted to fold inwardly or extend upward and outward flaringly, substantially as described, and for the purpose set forth.

2. In a straw-stacking machine, a carrier-frame consisting of a bottom board, upwardly-projecting side pieces, top boards hinged to the side pieces, straps secured to the top boards and having downward projections adapted to lie against the sides of the under side boards, and a hinged end piece, substantially as described, and for the purpose set forth.

3. In a straw-stacking machine, the windlass *sp*, mounted on a shaft, *s*³, the cogged gearing *cg* *cg'*, shaft *s*², and crank *cr*, the shaft *s*³ being provided with a ratchet engaging a pawl on the frame, as set forth, in combination with the chain *ch* and carrier-arm *P*, substantially as described, and for the purpose set forth.

In witness whereof I have hereto set my hand this 11th day of April, 1883.

LEWIS WM. HASSELMAN.
